UNITED STATES PATENT OFFICE.

JACOB S. BROWN, OF CARLISLE, PENNSYLVANIA, ASSIGNOR OF ONE-HALF
TO WILLIAM E. AND JOHN R. MILLER, BOTH OF SAME PLACE.

WELL DRILLING AND PIPING MACHINE.

SPECIFICATION forming part of Letters Patent No. 367,783, dated August 9, 1887.

Application filed July 12, 1886. Serial No. 207,804. (No model.)

To all whom it may concern:

Be it known that I, JACOB S. BROWN, a citizen of the United States, residing at Carlisle, in the county of Cumberland and State 5 of Pennsylvania, have invented certain new and useful Improvements in Combined Oil and Gas Well Drilling and Piping Machines; and I do hereby declare the following to be a full, clear, and exact description of the invention, 10 such as will enable others skilled in the art to which it appertains to make and use the same.

My invention relates to oil-well drilling and piping machines; and it consists in the construction and arrangement of the parts, which 15 will be more fully hereinafter described, and pointed out in the claims.

Heretofore in machines of this class the power as well as the operating parts of the device have been constructed separate and apart, 20 horse-power being generally used for running the mechanism, and when said mechanism has been unitedly constructed the changing or reversing of the running parts accomplished at different points of the machine, thereby requiring extra labor to keep it in desired working order.

One object of my invention is to provide a device having all the parts necessary to well-boring combined in one machine, the levers 30 for operating the various parts being situated at one portion of the device adjacent to the operating end of the drill.

A further object of my invention is to provide a drilling-machine in which the power is 35 transmitted from one shaft to another by positive gearing, the desired motion of said gearing in relation to the main driving-shaft being accomplished by clutches and controlled by suitable brakes which are actuated by levers.

A still further object of my invention is to 40 provide a machine wherein a main driving-shaft is mounted transversely thereof, upon which a series of gear of necessary speed impart motion, received directly from the engine, to a portion or all of the parts, which is governed by the result desired to be accomplished.

A still further object of my invention is to 45 provide a head-block carrying a sliding crank- 50 pin which gives two strokes to the drill at

one revolution of the said block, and which is adapted to be converted into a single operating-crank when desired.

A still further object of my invention is to provide a rope-centering device in connection 55 with the drill-reel, whereby the rope is adapted to be always fed directly to the head-block on its central line of motion.

A still further object of my invention is to provide an adjustable pulley arranged in a 60 folding derrick, whereby means are provided for shifting the working apparatus in connection therewith to give room for some other portion of the machine to have full operation.

A still further object of my invention is to provide a drilling-machine having a covering frame-work, a portion of which is extensible and adapted to receive a covering for the protection of the workmen at the fore part of the 70 machine during inclement or cold weather, thereby providing simple and effective means for the shelter of the machinery and of the operator.

A still further object of my invention is to 75 provide a folding derrick and stack and a top frame-work or covering formed partially telescopic, whereby all the parts may be so adjusted as to temporarily decrease the proportions of the machine, providing means for 80 bringing it within the regulation size for transportation and for convenience generally.

A still further object of my invention is to provide means, in connection with the drill or auger, whereby pipe may be driven by the 85 same mechanism and operation thereof as is used in drilling, thereby rendering the use of complicated and superfluous mechanism unnecessary.

A still further object of my invention is to 90 provide means in the form of an incline in connection with the wheels of the machine, as well as means for extinguishing the fire in the furnace, whereby the machine may be safely used for gas-well boring, and when premonitions of the presence of the gas appear the machine can be rolled away down the incline 95 and the fire quenched, thereby preventing the firing of the escaping gas.

A still further object of my invention is to 100

construct the parts of the machine in a simple and efficient manner, readily understood and handled, easily transported and set up in working position, safe, convenient, and accessible at all points, and the entire mechanism adapted to be operated from one point.

I attain these objects by the mechanism illustrated in the accompanying drawings, wherein like letters and figures of reference 10 indicate similar parts in the several views, and in which—

Figure 1 is a side elevation of my improved machine with the upper parts folded down. Fig. 2 is a view similar to Fig. 1, from the opposite side of the machine. Fig. 3 is a top plan view of the device with the roofing or top frame-work broken away. Fig. 4 is a front elevation of the machine with the derrick broken away. Fig. 5 is a top plan view of the machine with the frame-work in place. Fig. 6 is a side elevation of a portion of the machine mounted upon an incline and ready for gas-well boring. Fig. 7 is a detail view in front elevation of the head-block and gearing, 25 showing to one side thereof the block for converting said head-block into a single crank. Fig. 8 is a side elevation of the said head-block and gear-wheel. Fig. 9 is a plan view of the drill-reel-operating gear, the clutch and 30 operating-lever, and the inner wheel and brake, also showing the connection. Fig. 10 is a side elevation of the inner wheel and brake shown in Fig. 9. Fig. 11 is a front elevation of the adjustable pulley and a portion of the folding 35 derrick. Fig. 12 is a detail perspective view of the drill-auger with a tube-driving collar secured thereto.

A indicates the side bars of the frame, which rest upon and are secured to the bolsters B B, 40 to which in turn the axles C C of the wheels D D are secured.

Mounted upon suitable supplemental bolsters, E E, are longitudinal upright beams F F, in which the shafting of the device is mounted 45 on both sides of the machine, short longitudinal beams G G G being also secured to the frame-work described in the interior portion of the bed-work, and which are adapted to form bearings for the inner ends of the shorter 50 portions of the shafting. This bed frame-work may be constructed of metal, preferably cast, and may be placed in various positions to suit the desired arrangement of the mechanism.

Extending vertically upward from the beams 55 F F are uprights or supporting-pillars H H H H, which extend up and support the roofing frame-work, being connected to the side bars I I thereof. This top frame-work is constructed of tubing, preferably gas-pipe, and 60 the side bars or tubes I I are connected to the end tube, I', by couplings i i, the front portion of the frame being unconnected and the ends of the side pipes I I left open.

Connected to the front portions of the two 65 side bars A A are two beams, J J, which are inclined toward each other, as shown in Fig. 4, being strengthened by suitable braces, j j,

at their lower portions, said braces being connected at their other ends to the supplemental beams F F. These upright inclined beams J J extend some distance above the side tubes I I of the roofing frame-work, the said tubes in their front portions being suitably supported by braces i i, attached to the said uprights J J and surrounding the side tubes I I. As heretofore described, the uprights J J extend a short distance above the roofing frame-work or the side tubes I I, and are cut off. Inside of the said uprights J J two uprights or standards, J' J', continue upward, carrying out the 70 same gradual inward inclination as the uprights J J. These standards J' J' have their outer sides planed off vertically to correspond and engage with the inner sides of the outer uprights J J, which in like manner are planed vertically for a short distance. The said standards J' J' extend upward, as heretofore described, their height depending upon the class of work to be executed, and have suitable tie-braces, j j, and a sheave or pulley, j², mounted 75 in their uppermost portion.

In the lower portion of the uprights or standards J' J' a sliding pulley, K, is mounted, the shaft k of which is secured to the said uprights by suitable means. A shifting-lever, K', pivoted on a bracket, k', secured to one of the uprights J', engages with a groove-extension, k², formed on one side of the said pulley, said shifting-lever K' having a bifurcated projection, k³, engaging with the grooved extension. 80

To one side of the pulley or sheave K is a stop or guard, k⁴, in the form of a collar rigidly secured to the shaft k, and mounted at such a distance from either side of the uprights as to permit the pulley K to be slid into the central portion of the shaft k, midway between the two said uprights. By this means the pulley, when not required for use, can be shifted to one side and leave a clear working space for the other parts of the drilling apparatus. 85

The two sets of uprights or standards J and J' are pivoted by means of a rod or pintle, L, which passes through the said uprights, has screw-threaded ends, and is provided with clamping-nuts l l. Suitable braces j j connect 90 with the lower standards, J J, at or about the point where the pivoted rod or pintle L passes through the said standards, and extend down on an incline and are secured at their other ends to the supplementary beams F F. The front portions of the side bars or tubes I I are engaged by an extensible frame, M, the ends of which slide into the ends of the side tubes I I, and are adapted to be pushed in the said tubes, or drawn out, as may be desired. This extensible 95 frame may be constructed of suitable material, preferably iron wire of the required diameter, and bent into shape from one piece. To the front portion of this frame M is movably connected a supplemental frame, M', which is 100 adapted to form a roofing for this portion of the machine, and when in position for use rests against the upper standards, J' J'. The free end of this frame M' is formed with a loop or 105

depression, m , through which the ropes may pass during their operation. This frame M' is adapted to receive a covering of canvas or other suitable material applicable for the use

5 required, which may extend down around the front and sides of the frame M , and be carried to the ground and be secured, thus forming a covering or protection for the operator during inclement weather.

10 On the top of the side bars I and end bar, I' , is placed a suitable roofing material, N , which extends out slightly over the farthest projecting portions of the machinery below, thus protecting the working parts of the device 15 from injury by the weather. The said roofing N is provided with a longitudinal slot, n , and a transverse slot, n' , which slots connect with each other and provide means for allowing the ropes or lines to pass therethrough 20 while in operation. On the rear portion of the roofing N , at or about its central portion, a support, n^2 , is mounted, upon which the standards J J' rest when folded down.

In the rear portion of the machine a vertical boiler and furnace, O , is mounted, being supported at its lower portion between the beams A , and provided with suitable braces and stays, as o o o' , secured to various parts of the machine. This boiler has a jointed 25 stack, O' , which is hinged at the point o^2 , and having a spring-catch, o^3 , on the reverse side. By this means the stack may be lowered or folded down and secured when raised for working. When the said stack is folded down, 30 it is engaged by the circular retaining metallic clasp or ring o^4 , which is formed with a hinged joint and adapted to inclose the said stack and temporarily secure it in a stationary position.

35 In the forward portion of the machine a vertical engine, P , is mounted upon a suitable bracket, P' , which is supported by the bed frame-work of the device. This engine is connected with the boiler O by means of a suitable steam-feeding pipe, P^2 , having a throttle or other suitable cut-off valve, p , mounted therein, and adapted to regulate the flow of steam to or from the engine. A pipe, p^3 , forms the steam-exhaust, running into stack O' of the boiler and allowing the surplus steam to escape therethrough. This engine has suitable pitmen, p^4 , operated in a manner well understood, said pitmen extending downward and engaging with a crank-shaft, S' , mounted 45 in the bed frame-work, and having a fly-wheel, W , on its outer end, adjacent to the side beam, F . A spur-wheel, 1 , is mounted on this shaft S' , which meshes with another spur-wheel, 2 , on the main shaft S , which shaft extends across 50 the entire transverse width of the bed-frame, being boxed at each end in the beams F F . This wheel 2 is of larger diameter, and consequently of slower speed, than the wheel 1 , allowing the engine to be run at a rapid rate 55 of speed to attain the necessary power, said power being transmitted to the main shaft S through the medium of the slower wheel 2 ,

thus adapting the rapid running of the engine P to the required power and speed necessary to the regular and efficient running of the working mechanism.

On the opposite side of the frame-work, opposite to and in front of the engine P , a counter-shaft, S^2 , is mounted, on which a master gear-wheel, 3 , is secured, which meshes with a spur-wheel, 4 , on the main shaft S , and by which the said wheel 3 is given motion. This master-gear 3 is four times as large as the spur-wheel 4 , and consequently has one-fourth the motion of the said spur. On this counter-shaft S^2 , and ahead of the master-gear 3 , the head-block R is mounted and keyed. This head-block R is constructed with slideway r therein, which receives a sliding block, r' , which has a wrist-pin, r^2 , connected thereto, 85 on which a removable sheave or pulley, r^3 , may be mounted for some uses, and adapted to be removed when it may be desired to dispense with its use. In both ends of the said slideway r are mounted two cushions, r^4 r^4 , of 90 rubber or other suitable material, which ease the blow of the sliding block r' in its movement in the slideway r . This head-block R is keyed directly to the end of the counter-shaft S^2 , and has the direct motion therefrom. 95 To every single revolution of the said shaft S^2 the wrist-pin r^2 , in connection with the sliding block r' , gives two strokes to the drill or auger, the slide-block r' always sliding upward from the lowest portion of the slideway r in 100 the head-block R .

When it is desired to convert the head-block into a single operating-crank, a block, R' , as seen in Fig. 7, is inserted in the slideway r , under the sliding block r' , and the wrist or crank pin r^2 is held in a temporarily-fixed position and a single stroke to every revolution of the shaft s^2 given to the drill. This construction provides for the use of the drill when a stratum of broken rock or soft material is 110 struck, when it is not necessary to give the full effect of the double stroke of the drill or auger, as in drilling through a bed of rock.

On the one end of the main shaft S , a spur-wheel, 5 , is mounted, which is of equal diameter and time as the spur-wheel 4 , said wheel 115 meshing with another master gear-wheel, 6 , of the same diameter and time as the master-gear 3 . The spurs 4 and 5 are each provided with clutches 7 and 8 , which clutches adapt 120 their respective spurs to be thrown into or out of mesh with their connecting wheels. These clutches 7 and 8 have circular grooves 9 and 10 , which are engaged by the points of levers 11 and 12 , said levers being pivoted to a 125 bracket, 13 , secured to the side frame, F . Rods 14 and 15 are connected to the said levers 11 and 12 , which run to the front portion of the machine, and engage with operating-levers 16 and 17 , mounted in a rack 18 , composed of a 130 series of curved bars, said operating-levers having smaller levers engaging with the sectors formed in said curved bars, for a purpose which will be readily understood.

The master-wheel 6 imparts motion to the drill reel or drum T, being in direct connection therewith. Inside of the master-gear 6 is a wheel, W', which forms a guard for one side of the drill-reel T. A clutch, 19, is provided, one half of which is connected to the sides of the said master-gear 6 and the other half to guard-wheel W', and by means of which clutch the gear 6 can be thrown out of or into connection with and impart motion to the said drill-reel. On the outer side of the gear 6 a recessed flange, 20, is provided adjacent to the shaft S', which has journal-bearings in the two vertical brackets V V, secured on each side of the machine to the side beams, F F, and upon which shaft the said gear is mounted. This recess is engaged by a bifurcated arm, 21, which is mounted upon and extends upward from a rod, 22, which is mounted in the side of the bed-frame and extends to the front portion of the machine and adjacent to the levers 16 and 17, where it is provided with an operating-lever, 23. In raising or lowering this lever 23, which normally rests in a plane parallel to the plane of the front bolster of the machine, the gear 6 is thrown out of or into connection with the wheel W'. This wheel W' has a peripheral recess, which is engaged by a brake, 24, which is constructed of suitable thin strap metal. One end of this brake 24 is secured to a metallic strip, 25, attached to one of the supplemental bolsters E, and the other end is engaged by a rod, 26, which extends to the front of the machine and is provided with an operating-lever, 27, which is arranged and supported in a manner similar to the levers 16 and 17.

The drill-reel T extends across the entire transverse width of the machine, and has another guard-wheel, W'', mounted on the end thereof opposite to the wheel W'.

In the upper portion of the brackets V V a shaft, S', is mounted in the same vertical plane as the shaft S''. This shaft S' has mounted thereon the sand-pump reel U. A spur-wheel, 28, is mounted on one end of the shaft S', which meshes with the master-gear 6, and is one-fourth the size of the said gear, and consequently runs four times as fast. On the side of the reel adjacent to the spur 28 a wheel or disk, W'', having a flat periphery, is mounted, which acts as a guard for the reel at this point, and on the other side of the reel in like manner a guard-wheel, W', is mounted. The shaft S' is mounted in a vertically-sliding box, 29, Fig. 2, on the side adjacent to the spur 28. On one side of the vertical bracket V a projection, 30, is formed, to which the elbow of a bell-crank lever, 31, is pivoted, the one arm, 32, of said lever being pivoted to an arm, 33, connected to the sliding box 29, and the other arm, 34, of said lever 31 having a rod, 35, secured thereto, which passes down on an incline to the front of the machine, and is engaged by 65 an operating-lever, 36, arranged adjacent to and in a manner similar to the levers 16, 17,

and 27. By this means the spur 28 may be thrown out of mesh with the master-gear 6, and the use of the sand-pump reel U be dispensed with, if not desired to be operated. 70 Two arms, 37 37, extend outwardly from the upper portion of the bracket V, and thence inward toward the reel U, and have a semi-circular brake, 40, formed of strap metal, secured to the ends of the said arms 37. When 75 the spur 28 is thrown out of gear, consequently raising the wheel or disk W'', the said disk or wheel is thrown up against the brake 40 and the revolution of the reel U immediately stopped. 8c

Secured to the center of the forward supplemental bolster, E, is a rope-guide, 53, which is placed at the center of the said bolster and on a direct line with the wrist-pin r², and on a level with the rope on the drill-reel T. The 85 edges of this rope guide are flared on the rear side thereof, so as to form an easy passage for the rope without danger of cutting the same. By this means the rope from the drill-reel is always fed on a straight and direct line to the 90 wrist-pin r², no matter from what point of the reel it is unwinding, always preserving its straight feed without deviation.

In Fig. 12 I have illustrated an appliance to be used in connection with the auger 54 or 95 drill for driving tubes in a driven well. This consists, essentially, of a metallic collar, 55, which is held in place on the auger by a series of set-screws, 56, as shown—four in number. This device is operated by the head-block 100 crank R in the same manner as the drill itself, the end of the auger 54 fitting in the end of the tube, and the collar 55 striking the upper edge thereof at each stroke of the wrist-pin r² on the head-block. 105

In Fig. 6 I have also illustrated an incline, 57, to be placed under the wheels D of the machine to adapt it to be used for gas-well boring, the highest point of incline being situated at the forward or drilling end of the apparatus. Suitable blocks or chucks, 58, are placed under the wheels to keep the machine in a stable position. As shown in dotted lines, a steam-jet, 59, having connection with the steam-pipe of the boiler, is placed in the 110 furnace and adapted to extinguish the fire, being supplied with a suitable valve. When a premonition is given of the prevalence of gas, the valve of the jet 59 is opened and the fire extinguished, and the blocks or chucks 58 115 knocked from under the wheels D and the machine allowed to roll back down the incline 57 and out of the way of the escaping gas. By 120 this means firing of the gas and injury to the machine are avoided. 125

In addition to the drill or auger 54, as heretofore described, a sand-pump, 66, and screw are used in connection with the machine, as in other machines of this class, the auger or drill having a rope, 68, of any required length, 130 attached thereto, and the sand-pump is connected to a rope, 69. These ropes are wound

upon the reels T and U, and engage with the several parts of the machine in a manner which will be hereinafter described.

When the operation of drilling is commenced, the rope 68 from the reel T is placed in the guide 53, and thence under the sheave or pulley γ , on and up over the sheave or pulley δ in the top portion of the derrick. When the hole has been sufficiently started and the tools fed out their full length into the earth or rock, the drill and sand-pump alone are brought into operation in a manner similar to the operation of machines of this class.

If during the operation of the machine it is desirable to use any tool other than that engaging with the pulley K, the said pulley is pushed to one side, as heretofore described, and full sway and an unimpeded space allowed for operation of the other parts.

20 By means of the arrangement of levers 16, 17, 23, and 27 and 36, at one end of the machine, the whole mechanism, including the engine, can be operated by one workman. The parts to which the levers are connected and 25 operate can be thrown out or into gear or motion, which renders the machine economical in its action as to the saving of time and labor. The parts may be thrown out of gear and their imparted motion stopped by the brakes applied where necessary, thus preventing injury to the machine by avoiding a too rapid ascent of the drill or sand-pumps.

A further advantage of this machine is the head-block crank, which is convertible into 35 either a single or double stroke crank, which provides for a necessary change of operation of the machine when too rapid strokes of the drill are unnecessary when a soft stratum of earth or broken rock is struck, which, if 40 worked too rapidly, would chuck the drill or otherwise injure the machine.

This machine may be drawn from one place to another by means of horse-power; or the 45 wheels D D may be constructed in the form of traction-wheels or surrounded with a suitable traction-belt, and be driven directly from the engine and dispense entirely with the use of horse-power. In applying this tractive force well-known mechanical means will be used in 50 a manner similar to a traction-engine. By this means the machine is rendered convenient. As all the parts are combined, they will all be transported at one and the same time.

55 Suitable boxings are applied to the shafts wherever needed, as well as supports and braces for the various parts of the machine.

It is obvious that many minor details in the construction and arrangement of the parts 60 might be made and substituted for those shown and described without in the least departing from the nature and principle of my invention.

Having thus described my invention, what I claim as new, and desire to secure by Letters Patent, is—

1. In a combined well drilling and piping

machine, the combination of the drill and sand-pump reels and their gears, the main shaft, the counter-shaft having a double-acting head-block crank, the gears connecting 70 said shafts, and a series of levers and clutches constructed and arranged for controlling the operations of said shafts and reels, substantially as described.

2. In a combined well drilling and piping 75 machine, the combination of the supporting frame-work, the drill and sand-pump reels, the main shaft, the counter-shaft having a double-acting head-block crank, the gears for operating said shafts and reels, the clutches, the 80 brakes, and the devices for operating said clutches and brakes, substantially as described.

3. In a combined well drilling and piping 85 machine, the combination of the supporting frame-work, a main shaft provided with spurs or gears, the counter-shaft provided with the head-block crank and master-gear, the crank-shaft having a gear meshing with a spur on the main shaft, the lower reel-shaft having a master-gear meshing with a spur or gear on 90 said main shaft and operating the reels, and clutches and levers for separating or uniting the gears and allowing them to run together or independently of each other, substantially as described.

4. In a combined well drilling and piping 95 machine, the combination of a supporting frame-work, a main shaft mounted therein, a crank-shaft operated directly by the engine, a counter-shaft carrying a head-block crank 100 having two strokes to a single revolution thereof, and the drill and sand-pump reel-shafts, said shafts all being directly connected by meshing-spurs and master-gears, portions of which being adapted to be temporarily disconnected 105 from the main shaft by means of clutches operated by rods and levers, substantially as described.

5. In a combined well drilling and piping 110 machine, the combination, with the main shaft, carrying spur-gears and operated by the crank or engine shaft, of sand-pump and drill reel shafts mounted one above the other in the same vertical plane, intermeshing gears operating 115 said shafts from the main shaft, and clutches and a lifting elbow-lever secured to rods operated by hand-levers for connecting and disconnecting said parts, substantially as described.

6. In a combined well drilling and piping 120 machine, the combination, with the main shaft and spur-gears thereon and a counter-shaft, of a revolving head-block carrying a sliding crank adapted to give two strokes to one revolution, mounted on the end of the said counter-shaft, and a block adapted to be inserted under the sliding crank-pin and convert the entire crank from a double to a single acting crank, substantially as described.

7. In a combined oil and gas well drilling 125 and piping machine, the combination, with the main shaft and the drill and sand-pump

reels, of suitable guard-wheels and disks mounted on said reels, and circular and semi-circular strap-metal brakes engaging with said guard-wheels operated by suitable levers substantially as described.

5 8. The combination, with suitably-supported drill and sand-pump reels or drums, each provided with an intermeshing gear-wheel at one end, of devices for engaging and disengaging the gear-wheels of said drums or reels, consisting of an elbow-lever, a connecting-rod, and a hand-lever, substantially as described.

15 9. The combination, with the drill and sand-pump reels, arranged in vertical alignment and provided with an intermeshing gear-wheel at one end of each, and a clutch-controlled gear-wheel for imparting motion thereto, of 20 devices for engaging and disengaging the upper from the lower gear-wheel, and devices for stopping their motion, substantially as described.

10. In a combined oil and gas well drilling 25 and piping machine, the combination, with the main shaft and the drill and sand-pump reels, of the sand-pump-reel shaft mounted in a movable boxing at one side, said boxing having a depending arm, a bell-crank lever connected to said arm and pivoted in the vertical support, and a rod running to the forward part of the machine operating the said bell-crank lever to tilt the sand-pump reel and throw it out of gear, substantially as described.

35 11. In a combined oil-well drilling and piping machine, the combination of a double-acting head-block crank carrying a wrist-pin, to which the rope may be attached direct, a removable sheave or pulley adapted to be 40 mounted on said wrist-pin, and a detachable block adapted to be inserted under the sliding block of said wrist-pin, substantially as described.

12. In a combined oil-well drilling and piping machine, the combination, with the drill-reel rope and head-block crank, of a metallic guide secured to one of the frame-beams and adapted to guide the drill-rope from the drill-reel in a central line to the head-block crank, 50 substantially as described.

13. The combination, with the supporting bed-frame, of a folding derrick formed in two overlapping and foldable sections, and a single rod or pintle having screw-threaded ends

and passing entirely through and forming the 55 joint of said sections and provided with clamp-nuts for securing and rigidly holding the said sections in position, substantially as described.

14. In a combined oil and gas well drilling 60 and piping machine, the combination, with a supporting bed frame-work supporting the operating parts, of a roofing frame-work constructed of gas-pipe, and a covering having a longitudinal and transverse slot therein for the passage of the operating-ropes, substantially as described.

15. In a combined oil and gas well drilling 65 and piping machine, the combination, with the supporting bed frame-work having the several operating parts mounted therein, and of a roofing frame-work adapted to receive a covering, of a telescopic roofing in the front portion of the machine sliding in the open ends of the side pieces of the gas-pipe forming the roofing frame-work, and an extension 70 hinged to said telescopic roofing adapted to receive a cover or awning, substantially as described.

16. In a combined oil-well drilling and piping machine, the combination, with the folding derrick, of a sliding pulley mounted in the lower portion of the upper section of said derrick and adapted to be folded down with said section, and a lever for sliding said pulley to one side, whereby the tools attached to the rope passing over said pulley may be moved to one side and out of the way of the operation of the tools on the rope passing through the top sheave, substantially as described.

17. In a combined oil and gas well drilling 80 and piping machine, the combination, with the bed frame-work supporting the several working parts, of an extensible telescopic roofing covering said working parts and the forward end of the machine to protect the workman, the folding derrick and smoke-stack 85 adapted to be folded in different directions and rest on the roofing, and means for supporting and securing the several parts, substantially as described.

In testimony whereof I affix my signature in presence of two witnesses.

JACOB S. BROWN.

Witnesses:

JOHN ZINN,
S. H. GOULD.
